A. E. HOHMEISTER

FLUSH VALVE

Filed June 23, 1922

Inventor
Arthur E. Hohmeister

By *Walter J. Murray*

Attorney

UNITED STATES PATENT OFFICE.

ARTHUR E. HOHMEISTER, OF CINCINNATI, OHIO, ASSIGNOR TO THE JOHN DOUGLAS COMPANY, OF CARTHAGE, OHIO, A CORPORATION OF OHIO.

FLUSH VALVE.

Application filed June 23, 1922. Serial No. 570,344.

To all whom it may concern:

Be it known that I, ARTHUR E. HOHMEISTER, a citizen of the United States of America, and a resident of Cincinnati, in the county of Hamilton and State of Ohio, have invented a new and useful Improvement in a Flush Valve, of which the following is a specification.

My invention relates to flush valves and is adapted to be used in all positions where a flush valve is desirable, such, for example, as to flush water closets and the like.

An object of my invention is to provide a valve wherein operation of the valve may be nicely regulated, and the closing of which will not be affected by continued pressure on the valve actuating means.

Another object of my invention is to provide a valve for the purpose stated, wherein the parts are positive in operation.

Another object of my invention is to reduce the number of operative parts employed in valves of this type.

These and other objects are obtained by means described herein, and disclosed in the accompanying drawing, in which:

Fig. 1 is a vertical sectional view thru a valve embodying my invention, the valve parts being shown in their normal or closed relation.

Fig. 2 is a fragmental sectional view, on a reduced scale, showing the relation of parts of the valve after same had been actuated, and wherein pressure on the actuating means has not been released.

Fig. 3 is a sectional view on line 3-3 of Fig. 1.

The device of my invention comprises a casing 4, having a bore 5, extending lengthwise there-thru, intermediate the ends of which bore is formed an annular inwardly extending threaded flange 6. A sleeve 7 is mounted upon the flange 6 and the upper end of the sleeve is developed into a valve seat 8. A main valve 9 is adapted to engage the seat 8 thereby controlling communication between an intermediate chamber 10 formed above the sleeve 7 and a discharge or bottom chamber 11 communicating with a suitable discharge pipe 12. The valve carries a piston 13 which rides over the wall of the bore 5, and separates the intermediate chamber 10 from a pressure chamber 14 formed at the top or head of the valve. A suitable cap 15 forms a closure for the top

of the casing and for the pressure chamber 14. The valve stem 16 of the valve 9 has a chamber 17 formed within it, and within the chamber 17 is contained the head 18 of a pin 19. A suitable bore 20 is formed in the lower wall 21 of the chamber 17, and the pin 19 extends thru this bore 20 into the discharge chamber 11. The pin bears such relation to the bore that it may be rocked in the bore, so as to assume a position as shown in dotted lines in Fig. 1. The head 18 serves to preclude the pin from falling into the discharge chamber 11 and to impart to the pin an upward movement at those times when the valve 9 is moved upwardly. The intermediate chamber or supply chamber 10 is in communication with a suitable water supply by means of the supply pipe 22. The casing 4 has formed in it a by-pass 23, the by-pass communicating with the pressure chamber 14 and the relief valve chamber 24. The wall 25 of the by-pass 23 extends thru that portion of the casing thru which the water must pass as the water flows from the supply pipe 22 into the intermediate chamber 10. This part of the by-pass is given a tube-like structure, as shown in Fig. 3, and in this tube-like portion of the by-pass is formed a valve seat 26 adapted to be engaged by the regulating valve 27. The regulating valve 27 determines the flow into the pressure chamber 14. A relief valve seat 28 is formed on the casing 4 at one end of a bore 29 thru which communication between the discharge chamber 11 and the relief valve chamber 24 may be effected. The auxiliary or relief valve 30 normally engages the valve seat 28, and is yieldingly retained in such engagement by a spring 31 contained within the relief valve chamber 24, the opposite ends of the spring engaging the valve 30 and the cap 32 forming a closure for the relief valve chamber. The cap 32 has formed in it a bore 33 in axial alignment with the stem 34 of the relief valve, and the stem 34 extends reciprocally into the bore 33. The inner end 35 of the stem 34 is disposed within the discharge chamber 11 immediately adjacent the pin 19. When the pin 19 is rocked to a position as shown in dotted lines in Fig. 1, the relief valve is unseated and the water under pressure in the pressure chamber 14, by-pass 23, and the pressure valve chamber 24 may escape into the discharge chamber 11. As soon as the pressure upon the upper

face of the piston 13 is relieved, the pressure of the water within the intermediate chamber 10 lifts the valve 9 whereupon a flow of water may pass from the supply pipe 22 and the intermediate chamber 10 into the discharge chamber 11.

Any suitable means may be provided for rocking the pin 19. A simple and suitable mechanism for this purpose is disclosed 5 10 herein and comprises a plunger 36, the inner end of which is adapted to engage the lower end of the pin 19, and the outer end of which carries a head 37 the opposite sides of which are engaged by a spring 38 and an 15 actuating handle 39. The spring 38 yieldingly retains the push rod in its normal position, the yielding resistance of the spring being sufficient to retain the actuating handle 39 to its normal position as shown in full 20 lines in Fig. 1. A collar 40 mounted on the casing 4 and within which the plunger 36 is reciprocally contained, carries an upwardly extending yoke 41 the branches 42 and 43 of which lie on opposite sides of the 25 pin 19, and preclude the pin from slipping side-ways from between the plunger 36 and the inner end of the relief valve 30 when the push rod is actuated.

The operation of my device is as follows: 30 Normally the parts assume the relation shown in full lines in Fig. 1. At this time the valve 9 engages its seat 8, and the relief valve engages its seat 28. When the actuating handle 39 is moved to the position shown 35 in dotted lines in Fig. 1, the plunger 36 is brought into engagement with the pin 19 and rocks the pin to such extent that the pin engages the relief valve and unseats the relief valve, whereupon the pressure within 40 the pressure chamber 14 being relieved, the water flowing into the intermediate chamber 10 unseats the valve 9 as heretofore explained. As the valve 9 is lifted under the influence of the pressure within the chamber 45 10, the pin 19 is lifted to such extent that its lower end is raised above the plunger 36, whereupon gravity returns the pin 19 to a position in axial alignment with the normal position of the pin. The spring 31 50 in the relief valve chamber then seats the

relief valve and the water flowing thru the regulating valve in the by-pass 23 builds up the pressure within the pressure chamber 14 to such extent that the valve 9 is brought into engagement with its seat 8. 55 The chamber 17 in the stem of the primary valve 9 is made of sufficient length that the valve 9 may engage its seat 8 although the lower end of the pin may still engage the upper surface of the plunger 36 as shown 60 in Fig. 2.

What I claim is:

1. In a flush valve the combination of a casing, having a closed end, a discharge opening adjacent to the end opposite to its closed end, an inlet opening in its side, a main valve seat between its inlet and its discharge openings, a by-pass connecting its closed end and its discharge opening, and an auxiliary valve seat surrounding the opening of the by-pass into its discharge outlet, a main reciprocatory valve within the casing and adapted to seat upon the main valve seat, an auxiliary valve within the casing and adapted to seat upon the auxiliary valve seat, a reciprocatory operating device in the casing and opposite to the auxiliary valve, and a pin swiveled to the main valve depending between the auxiliary valve and the operating device and adapted to be 65 70 75 brought into contact with the auxiliary valve by the reciprocation of the operating device and to be carried by the main valve out of the path of the operating device.

2. A valve device comprising two valves 85 and having a single by-pass therein, one the main valve which controls a flow of water, the other an auxiliary valve mounted in the by-pass for controlling the main valve, means carried by the main valve adapted to 90 actuate the auxiliary valve and to be rendered inoperative upon said auxiliary valve by the action of the main valve, a fixed guide for the first mentioned means, and means for rendering said first mentioned 95 means operative upon the auxiliary valve.

In testimony whereof, I have hereunto subscribed my name this 22nd day of June, 1922.

ARTHUR E. HOHMEISTER.
